JOHN D. TOMPKINS, OF VALATIE, NEW YORK, AND FREDERICK H. FULLER, OF VANCOUVER, WASHINGTON; LIDA M. FULLER, OF VANCOUVER, WASHINGTON, EXECUTRIX OF SAID FREDERICK H. FULLER, DECEASED, ASSIGNEES TO TOMPKINS, HAWLEY, FULLER COMPANY, OF VALATIE, NEW YORK, A CORPORATION OF OREGON

METHOD OF AND MACHINE FOR MAKING PAPER

Application filed May 5, 1927. Serial No. 188,966.

The present invention aims to enable paper to be manufactured with fewer and simpler steps and machinery, particularly by eliminating the use of press rolls with their attendant expensive clothing and the large amount of power required to operate them, as well as their tendency to crush and weaken the paper sheets and cause sheet breakage.

Another object of the machine is to facilitate the making of plain, glazed, creped or water-marked papers on the same machine with only slight changes or adjustments.

Further objects and advantages of the invention will be in part obvious and in part specifically pointed out in the description hereinafter contained which taken in conjunction with the accompanying drawing, discloses a machine by the use of which paper may be made in accordance with the invention. In the drawing—

The single figure is a diagrammatic side view of the main parts of a machine adapted to operate in accordance with the invention.

The invention is illustrated as applied to a machine of the Fourdrinier type, having a head-box 1 from which the pulp flows on to a forming member 2, having the usual tension devices, breast roll 3 and couch roll 4, the width of the pulp course being regulated by the usual deckle-straps 5.

As the newly formed paper web travels along the forming wire 2, a felt apron 6 is caused to overlie and travel along a section of the forming wire in such manner that the web is supported between the two. We have found that a sufficient amount of water may be extracted from the web at the above stage of its manufacture, to enable the web to be led directly therefrom to the driers, meaning by "directly" that no press rolls need be interposed between the forming wire and the drying section of the machine. As shown a plurality of suction devices 7, which may be known types of suction boxes, are placed under the above mentioned section of the forming wire in such manner as to draw water downwardly in successive stages from the paper web and felt apron to the forming wire. We prefer furthermore to augment the action of the suction by dry air blasts directed down-

wardly on to the felt apron from suitable blast pipes 8, the blasts giving added activity to the movement of the water or moisture in its process of extraction and also serving to absorb a certain amount of water in passing through the unpressed paper web. Each air blast with its accompanying suction box may remove about the same amount of water from the uncompressed sheet as would be removed by a pair of press rolls, whereby it becomes possible to take the sheet directly from the forming wire without passing between press rolls or being otherwise subjected to mechanical pressure except the relatively light pressure of the couch rolls, to the drying section of the machine. As shown the felt apron 6 carries the paper web along past the guide rolls 9 and 10 to adjustable pressure rolls 11 and 12 which press the felt and the paper web against the periphery of the first roll 13 of the drier section of the machine. We prefer to locate the roll 11 below the center of roll 13 and the roll 12 above the center thereof, as shown in the drawing. The roll 13 usually will be a heated roll, although it will be understood that the degree of heat may be regulated, or heating omitted, as different conditions of operation may make desirable. The roll 13 preferably is much larger than the succeeding rolls 14 of the drier section of the machine which latter may be of conventional character.

After leaving the roll 13 the felt apron 6 may pass along to a suitable shower pipe 15 for the purpose of cleansing the apron with hot or cold water as occasion may require. An adjustable scraping-board 16 also may be employed which acts to loosen up any foreign particles from the working side of the felt apron. A suction box 17 may also be employed to loosen foreign particles from the exposed surfaces of the felt apron 6, after which the latter passes down around a guide roll 18 into contact with the newly formed paper web on the forming wire.

In the manufacture of a paper sheet as above outlined, the extraction of the necessary amount of water prior to the drying operation is accomplished entirely by the suction devices 7 and the air blast issuing from

pipes 8 with the result that the paper web reaches the roll 13 in a substantially uncom-
pressed condition. The rolls 11 and 12 act-
ing against roll 13 apply the proper degree
5 of pressure to the web and the pressure may
be heavy enough to produce a glaze if desired.
Either or both of the rolls 11 and 12 further-
more may be provided with raised surfaces to
produce any desired marks or figures on the
10 paper web.

If it is desired to produce creped paper, the
paper web may be permitted to pass around
roll 13 until it is creped by the action of a
15 blunt-edged scraper 19, the degree of crepe
being proportional to the bluntness of the
edge of the scraper.

In creping the drying rolls 14 will be slowed
down so as not to stretch the crepe and the
roll 13 will be heated to give the creping a
20 better permanent set.

While the invention has been described as
carried out by the use of a specific apparatus,
it will be obvious that many changes may be
25 made therein without departing from its
essentials as set forth in the following claims.

We claim:

1. A paper making machine, comprising a
web forming member, a felt apron overlying
30 a section thereof, means for subjecting said
section of the forming member and the felt
apron to the combined action of air blast and
suction devices and a drying roll, said felt
apron leading directly from the forming
member to the drying roll.

2. A paper making machine, comprising a
web forming member, a felt apron overlying
a section thereof, a plurality of suction boxes
underlying said section of the forming mem-
ber, a plurality of air blast devices overlying
40 corresponding sections of the felt apron, and
a drying roll, said felt apron leading directly
from said forming member to said drying
roll.

3. A paper making machine, comprising a
45 web forming member, a felt apron overlying
a section thereof, suction devices underlying
said section of the forming member, and a
drying roll, said felt apron leading directly
from said forming member to said drying
50 roll, together with rollers for pressing said
felt apron and the paper web carried thereby
against the drying roll, one of said rollers
being located below and the other above the
center of the drying roll.

55 4. A paper making machine, comprising a
web forming member, a felt apron overlying
a section thereof, suction devices underlying
said section of the forming member and a
drying roll, said felt apron leading directly
60 from said forming member to said drying
roll, and a scraper blade adapted to engage
said drier roll.

5. The method of making paper which com-
prises forming a paper web upon a forming
65 member, moving a traveling apron along over

the web while the latter is supported by the
forming member, applying suction to the web
through the forming member while the web
is held between the apron and such member,
and then leading the apron carrying the par-
70 tially dried web directly to a drier roll.

6. The method of making paper which
comprises forming a paper web upon a form-
ing member, moving a traveling apron along
75 over the web while the latter is supported
by the forming member, applying air blasts
through said apron and suction through said
forming member to the paper web in suc-
cessive stages while the latter is between the
80 felt apron and forming member, and then
leading the apron carrying said web directly
into contact with a drier roll.

7. The process of making a paper web
which comprises forming a paper web upon
a forming member, moving an apron into
contact with said web while supported by the
forming member, extracting the amounts of
water from said web which are necessary to
be extracted prior to the drying operation
by the aid of suction devices without the use
85 of mechanical pressure, then leading the
apron carrying said web into contact with a
drier.

8. A paper making machine, comprising a
web forming member, a felt apron overlying
90 a section thereof, suction devices underly-
ing said section of the forming member and a
drying roll, said felt apron leading directly
from said forming member to said drying
roll and means for spraying water on the felt
95 apron after the paper web has been directed
to the drying roll.

9. A paper making machine comprising,
a web forming member, a felt apron overly-
100 ing a section thereof, suction devices under-
lying said section of the forming members
and a drying roll, said felt apron leading di-
rectly from said forming member to said dry-
ing roll, and means for scraping loose mate-
rial from the felt apron after the paper web
105 has been directed to the drying roll.

10. A paper making machine comprising,
a web forming member, a felt apron overly-
110 ing a section thereof, suction devices under-
lying said section of the forming member and a
drying roll, said felt apron leading directly
from said forming member to said drying
roll, and suction means located on one side
115 of the felt apron for loosening foreign parti-
cles thereon after the paper web has been di-
rected to the drying roll.

11. A paper making machine comprising,
a web forming member, a felt apron overly-
120 ing a section thereof, suction devices under-
lying said section of the forming member and a
drying roll, said felt apron leading directly
from said forming member to said drying
roll, and means for cleaning the felt apron of
125 any adhering foreign matter after the paper
web has been directed to the drying roll.

12. Method of making paper which comprises forming a paper web, applying suction and an air blast to the web while it is held between porous belts and then passing the partially dried web directly to a drier roll.
- 5 13. A method of making paper, which comprises, forming a paper web upon a forming member, moving a traveling apron along over the web while the latter is supported by the forming member, applying suction to the web through the forming member while the web is held between the apron and such member, and then leading the paper web with the apron onto a drier roll, and applying pressure to said web and said apron at a plurality of places while said web and said apron are carried on the drier roll.
- 10 14. A method of making paper, which comprises, forming a paper web upon a forming member, moving a traveling apron along over the web while the latter is supported by the forming member, applying air blasts to said apron and suction through said forming member to the paper web in successive stages while the latter is between the felt apron and the forming member, leading the apron carrying said web directly to a drier roll and applying mechanical pressure to the web while on the drier roll.
- 15 15. A method of making paper which comprises forming a paper web upon a forming member, moving a traveling apron along over the web while the latter is supported by the forming member, applying suction to the web through the forming member while the web is held between the apron and such member, leading the apron carrying the partially dried web directly to a drier roll, and applying mechanical pressure to the web while on the drier roll.
